UNITED STATES PATENT OFFICE.

FRITZ EICHEBT, OF BERLIN, GERMANY, ASSIGNOR TO THE FIRM OF GREIF AND SCHLICK, OF COBURG, GERMANY.

DYNAMO-ELECTRIC GENERATOR.

1,145,575.

Specification of Letters Patent.

Patented July 6, 1915.

Application filed March 18, 1912. Serial No. 684,567.

To all whom it may concern:

Be it known that I, FRITZ EICHEBT, a subject of the German Emperor, residing at Berlin, in Germany, have invented certain 5 new and useful Improvements in Dynamo-Electric Generators, of which the following is a specification.

The present invention relates to dynamo electric generators which are driven by 10 prime movers working at varying speeds, as for example a bicycle wheel or part of the mechanism of a motor car or the like, where the current is used for feeding electric glow lamps, the dynamo armature being, in the 15 case of bicycles, commonly driven by a friction wheel in contact with one of the road wheels. If electric generators of this description are designed to supply sufficient current at comparatively low speeds of the 20 prime mover, the pressure of current is liable to become too high for the lamps at the higher speeds. If the generator is designed to supply the proper current at the higher speeds, the lamps will be dim when 25 the velocipede or vehicle slows down.

The object of the present invention is to provide an improved automatic device for regulating the current furnished by the generator. To this end I use a device whereby 30 a coil on the armature is automatically short-circuited upon itself when a certain speed is reached, so that the current generated in this coil has a de-magnetizing effect which weakens the current supplied to 35 the external circuit. Moreover, if the short-circuited coil is part of the normal armature winding, the short-circuiting reduces the number of ampere-turns whereby current is supplied to the external circuit.

40 The automatic device which I use is a centrifugal contact device or switch in a shunt connected to the armature coil.

The invention is illustrated in the accompanying drawing in which:—

45 Figures 1 and 2 are respectively an elevation of the generator, and a diagram of the armature coil, illustrating in a purely diagrammatic fashion the short-circuiting of a portion of the coil. Figs. 3, 4 and 5 show 50 a preferred form of the centrifugal contact device or switch.

Referring in the first place to Figs. 1 and 2, the winding on the armature 7 comprises two sections 8 and 9 in series with each 55 other. The end 10 of the winding is joined

to the lamp circuit, whereas the other end is connected to the machine at 11, and thence to the lamp circuit. The brushes for supplying current from the armature 7 to the outer circuit are omitted in the drawing for the 60 sake of clearness. The junction 12 of the two sections 8 and 9 is connected with a contact 13 insulated from the armature.

When the centrifugal force of the rotating armature is sufficiently high to cause the 65 lever 15, pivoted at 14 to the armature, to overcome the pull of the spring 16, and move as indicated by the arrow, the section 9 is short circuited by the lever 15 making contact with the contact 13, so that the electro-motive force of the generator is reduced. The current in the short circuit of coil section 70 9 also has a de-magnetizing effect weakening the potential difference between 10 and 11, and this effect increases with the 75 said current, that is to say with the speed of the armature. The coil section 9 assists in the production of useful current until it is short circuited.

Figs. 3, 4 and 5 are respectively a side 80 elevation, partly in section, an end elevation, and a plan view of one form of the centrifugal switch which I may use. The drum armature α has in one pole-piece a groove, in which is embedded a springy metal strip 85 b , held in position by a screw c in such manner that one end of the strip can swing outward under the influence of centrifugal force. This free end of the strip b is bent over one edge of the pole-piece and has a 90 lateral extension normally located at a certain distance from a pin d inserted in the end of the armature and insulated from the latter. When the metal strip b moves outward by centrifugal force, the lateral extension thereof touches the pin d . The strip is connected to one terminal of the coil section 95 to be short circuited, and the pin d is connected to the other terminal.

What I claim as my invention and desire 100 to secure by Letters Patent in the United States is:—

1. In a dynamo electric generator the combination of an armature, two coil sections on said armature, one of said coil sections being arranged to weaken the field of the generator by the magnetic effect of current flowing in said coil section, and a switch on said armature actuatable by centrifugal force, adapted to short circuit said 105 110

field weakening coil section upon itself at a predetermined armature speed.

2. In a dynamo electric machine the combination of an armature, two coil sections in series with each other upon said armature, a fixed switch contact upon said armature electrically connected to the junction between said coil sections, and a switch lever carried by said armature, electrically connected to the end of one of said coil sections

and arranged to be thrown against said contact by centrifugal force at a predetermined armature speed.

In witness whereof I have signed this specification in the presence of two witnesses.

FRITZ EICHERT.
